UNITED STATES PATENT OFFICE.

DAVY VANCE SICKMAN, OF DENVER, COLORADO.

HYDRAULIC CARTRIDGE WITH INDEPENDENTLY-OPERATING PISTONS.

1,191,138.

Specification of Letters Patent. Patented July 11, 1916.

Application filed July 13, 1915. Serial No. 39,684.

To all whom it may concern:

Be it known that I, DAVY VANCE SICKMAN, a citizen of the United States, residing in the city and county of Denver and State of Colorado, have invented certain new and useful Improvements in Hydraulic Cartridges with Independently-Operating Pistons; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in hydraulic cartridges of the class adapted for breaking down coal or other material in mines, my object being to provide a construction of this class of such character that one or more of the pistons of the bar, may be operated independently of one or more other pistons, thus making it practicable to control the ejection of the pistons of the bar, as may be desired.

A cartridge of this class consists of a bar provided with chambers in which are located pistons adapted to be ejected by liquid under pressure for purposes of breaking down the coal or doing other similar or like work where great power is required and but little space allowed for operating purposes.

Heretofore so far as I am aware no provision has been made in this art for the controlling of the ejection of one or more of the pistons of a cartridge of this class, while one or more other pistons remain idle or inactive or are more slowly ejected than the others.

In my improvement two distinct conduits are provided one being in communication with a number of the piston chambers and the other in communication with other piston chambers of the same cartridge. One of these conduits may be termed the main conduit and the other the auxiliary conduit, the latter being relatively short and in communication with the main conduit just beyond the breast of the bank of coal or other material to be broken down, the communicat-

ing passage between the main and auxiliary conduits being controlled by a valve with which the auxiliary conduit is equipped.

Having briefly outlined my improved construction, I will proceed to describe the same in detail, reference being made to the accompanying drawing in which is illustrated an embodiment thereof.

In this drawing, —Figure 1 is a top plan view of a hydraulic cartridge equipped with my improvement. Fig. 2 is a vertical section taken on the line 2—2, Fig. 1, showing two of the pistons partially ejected. Fig. 3 is a fragmentary top view illustrating the right hand extremity of the construction shown in Figs. 1 and 2, but illustrating the conduit members beyond or toward the right. Figs. 4 and 5 are cross sections taken on the lines 4—4 and 5—5, Fig. 1, shown on a larger scale. Fig. 6 is a cross section taken on the line 6—6, Fig. 3, looking toward the left, shown on a larger scale. Fig. 7 is a section similar to Fig. 5, but with the pistons and the tubes carried by the bar removed.

The same reference characters indicate the same parts in all the views.

Let the numeral 5 designate the bar of my improved hydraulic cartridge. In this bar are formed chambers 6 for pistons 7 which are mounted to move outwardly through openings in the bar on one side, it being assumed that the bar when in place in an opening bored for the purpose, will be so arranged that the open extremities of the piston chambers will be directed downwardly. In this event the hole to receive the bar is formed close to the roof and between the latter and the bank of coal to be broken. Each of these pistons is provided with a gasket or cup leather 8 held in place by a washer or securing plate 9 secured by cap screws 10 or other suitable fastening devices. The pistons are prevented from entirely escaping from their chambers by means of stop lugs or relatively short plates 12 held in place by screws or other fastening devices 13, the said lugs having tongues 14 which enter grooves 15 formed in the opposite sides of each piston. The upper extremi-

ties of the grooves 15 are closed as shown at 16 forming shoulders which engage the tongues of the stops, when the pistons have been ejected to the desired limit.

- 5 In my improved construction I employ a main conduit 17 and an auxiliary conduit 18 for introducing the liquid under pressure for piston ejecting purposes. The main conduit as shown in the drawing is centrally 10 arranged with reference to the longitudinal axis of the cartridge bar and its passage 19 is in communication with a perforation 20 extending transversely at the forward end of the bar, its outer extremity being in 15 communication with the forward end of a passage 21 in a tube 22 which is located in a groove 23 formed lengthwise of the cartridge bar and open on one side to receive the tube. This opening may be filled with 20 any suitable material for the purpose of protecting the tube and securing it in place, or it may be brazed or electrowelded in place. It is more economical and satisfactory to employ tubes in open grooves in 25 bars of this class, than to attempt to bore long passages through the bars for the liquid or other fluid to be employed. Furthermore if a tube should get clogged or stopped up while in use, it could be readily 30 removed from the bar for the purpose of overcoming the difficulty, whereas if a long passage formed in the solid portion of the bar should become stopped, great difficulty might be experienced in cleaning it out. 35 Tubes 22 may be made of such material that they will withstand the pressure of the liquid, and they have the advantage that they may be readily put in position and removed. The passage 21 of the tube 22, is in 40 communication with the chambers 6 of the rearmost two pistons 7, by means of passages 24, but the passage 21 is not in communication with either of the chambers 6 of the foremost two pistons 7. These last 45 named chambers, however, are in communication by short passages 25 with the passage 26 of a tube 27, set into a groove 28 formed in the opposite side of the bar from the groove 23, the passage 26 being also in communication with the auxiliary conduit 18, which is in communication with the passage 50 19 of the main conduit by a branch passage 29 leading to an opening 30 which terminates in a perforation 31 in communication 55 with the passage 32 of the conduit 18. The passage of liquid from the main conduit to the auxiliary conduit is controlled by a valve 33 having a hand wheel 34 accessible beyond the breast of the bank of coal or other material to be broken down.

60 The manner of tapping the tubes 22 for the purpose of placing their passages in communication with the piston chambers of the bar, is illustrated in Fig. 7, which 65 it may be assumed is taken on the same line

as Fig. 5. A hole 35 may be bored from the top of the cartridge downwardly in such a manner as to intersect the passage of the tube 27, while another hole 36 may be bored from the outer surface of the bar inwardly, 70 its inner extremity communicating with the inner extremity of the piston chamber, but intersecting the bore. The outer portions of the bores 35 and 36 may then be plugged as shown at 37 and 38. 75

The manner of tapping the tube 22, is substantially the same as employed in connection with the tube 27, and therefore need not be explained in detail, the arrangement of the passages 35 and 36, being indicated 80 by dotted lines in Fig. 7.

From the foregoing description it will be understood that in the use of my improved cartridge, if the valve 33 is closed, the liquid will enter the rearmost two chambers 6 85 alone and eject the corresponding pistons 7. If the operation of these pistons is sufficient to break down the block of coal, the foremost two pistons need not be operated. However, should the latter be needed it will 90 only be necessary to open the valve 33 when the liquid will pass into the chambers 6 of the foremost two pistons, and eject the latter for the purpose of completing the coal breaking-down act. 95

This construction of cartridge is exceedingly advantageous as compared with those cartridges of such construction that the pistons are simultaneously or approximately simultaneously subjected to the influence of the liquid pressure, since with this last named style of cartridge, the pistons which are nearer the front face of the block of coal, will be first ejected and the degree of their ejection will be in proportion to 100 their nearness to the forward extremity of the cartridge, since the nearer the piston is to the front end of the cartridge and consequently the nearer it is to the front face of the block of coal, the less the resistance 110 to its ejection. Consequently if all of the pistons from front to rear are simultaneously subjected to the action of the fluid under pressure, the rearward pistons will be but slightly ejected, while the force of the 115 fluid will be expended upon the pistons farther in front, with the result that the front end of the block of coal only will be broken down, making the work exceedingly unsatisfactory. My improved construction 120 of cartridge as set forth in this application is adapted to overcome this difficulty, since the fluid pressure may be applied to the rearward pistons only, until such time as they have been sufficiently ejected to need 125 the coöperation of the forward pistons, in which event the latter may be advantageously utilized. The fluid may be applied to the forward pistons, by simply opening the valve 33 which is accessible to the operator. 130

It is preferred to employ a valve 40 located between the branch orifice 29 and the forward extremity of the bar, so that the passage of the liquid or other fluid under pressure to the rearwardly located piston chambers, may be regulated and controlled independently of the passage of such fluid through the auxiliary conduit 18 to the forwardly located piston chambers. In other words by employing a valve 40 located as stated and as indicated in Fig. 3, of the drawing, it becomes practicable to regulate the speed of travel during the ejection of the rearwardly located pistons as compared with the forwardly located pistons. For instance if the fluid in equal volume were delivered to both sets of pistons, the forwardly located pistons would travel much faster than the rearwardly located pistons for the reason that the latter are subjected to greater resistance, due to the greater difficulty in moving the block of coal downwardly, the nearer the pressure is applied to the adhering rearward wall. As it is not desirable that the forward part of the block shall move faster than the rearward part, owing to the tendency that such operation would have to break off the forward end of the block leaving the rearward end adhering, by virtue of the employment of the two valves 33 and 40, I may deliver a relatively greater volume of fluid to the rearwardly located pistons than to the forwardly located pistons and by virtue of this difference in volume may cause an even travel of the two sets of pistons, or cause them to travel in such a manner as to advantageously cooperate in the performance of the coal-breaking-down function. Furthermore it is evident that by the employment of the two valves the fluid may be cut off from either set of piston chambers, while it is allowed to pass to the other set of chambers. It should also be understood that there may be one or more auxiliary conduits. While only one is shown in the drawing, it will of course be understood that an additional number may be employed if desired and as the additional one or more other auxiliary conduits, would be mere duplication it has not been considered necessary to illustrate such construction in the drawing.

Having thus described my invention, what I claim is,

- 55 1. A hydraulic cartridge having a plurality of piston chambers, pistons therein and means for introducing fluid under pressure to certain of said chambers independently of other chambers.
- 60 2. A hydraulic cartridge having a plurality of piston chambers, pistons therein, and a number of conduits for carrying fluid under pressure, one conduit being in communication with one or more chambers of the cartridge and another conduit in com-

munication with one or more other chambers, and valve controlled means for regulating the passage of fluid to one set of chambers.

3. A hydraulic cartridge having a number of piston chambers arranged at suitable intervals from front to rear, a conduit in communication with the rearmost chamber, and a distinct conduit in communication with the foremost chamber. 70

4. A hydraulic cartridge including a bar having a number of piston chambers arranged at suitable intervals from front to rear, a main conduit having its passage in communication with certain rearwardly located chambers, an auxiliary conduit whose passage is in communication with certain forwardly located chambers, and means for cutting off the fluid supply from one conduit while it is passing through the other conduit. 75 80

5. A hydraulic cartridge having a number of piston chambers suitably spaced from front to rear, a main conduit having its passage in communication with certain rearwardly located chambers, an auxiliary conduit having its passage in communication with certain forwardly located chambers, the two conduits being in communication by a branch passage, and a valve for controlling 95 the passage of fluid from the main to the auxiliary conduit. 90

6. A hydraulic cartridge composed of a bar having piston chambers, and tubes set into grooves formed in the bar and having 100 their passages in communication with the piston chambers.

7. A hydraulic cartridge consisting of a bar having piston chambers, and tubes set into grooves formed in the bar, the said 105 tubes being in communication with the piston chambers, and means for securing the tubes in place.

8. A hydraulic cartridge having a plurality of piston chambers, pistons therein, 110 and means for controlling the introduction of fluid under pressure to certain of said chambers independently of other chambers.

9. A hydraulic cartridge having a plurality of piston chambers, a conduit leading 115 to one chamber, a second conduit leading to another chamber, and means for equipping each conduit to permit the independent control of the fluid through the respective conduits.

10. A hydraulic cartridge having a plurality of pistons arranged lengthwise thereof from front to rear, conduits in communication with the respective piston chambers, and means applied to each conduit for regulating the passage of fluid therethrough, independently of such passage through any other conduit. 125

11. A hydraulic cartridge equipped with a number of piston chambers and pistons, 120

the said cartridge comprising a bar having chambers formed therein lengthwise thereof, conduits in communication with the respective chambers, and means applied to the respective conduits to permit the varying of the volume of fluid introduced to the respective conduits.

Copies of this patent may be obtained for five cents each, by addressing the "Commissioner of Patents, Washington, D. C."

In testimony whereof I affix my signature in presence of two witnesses.
